UNITED STATES PATENT OFFICE.

LEOPOLD LINDENTHAL, OF NEW YORK, N. Y.

DESIGN FOR UPHOLSTERY-TRIMMING.

SPECIFICATION forming part of Design No. 11,865, dated July 13, 1880.

Application filed May 18, 1880. Term of patent 7 years.

To all whom it may concern:

Be it known that I, LEOPOLD LINDENTHAL, of the city, county, and State of New York, have invented a new and original Design for 5 Upholstery-Trimmings, of which the following is a full, clear, and exact description, reference being had to the accompanying drawings, making part of this specification, in which—

10 Figures 1 and 2 represent front views of two forms of my improved upholstery-trimming.

Similar letters of reference indicate corresponding parts.

This invention has reference to an improved 15 design for upholstery-trimmings; and it consists of a trimming with a center band which is spread out at suitable intervals, so as to form ornamental flowers.

In the drawings, A is the body of the trimming, which is provided with a center band, 20 B, of any suitable color and width. At suitable intervals the continuity of the center band,

B, is interrupted, and a flower, C, of somewhat greater width, formed, as shown in Figs. 1 and 2. This flower is preferably puffed up or raised, 25 so as to impart a certain boldness of design to the trimming. The remaining portions of the trimming are finished in any desired style or design, the essential feature of my design being the center band with enlarged flowers. 30

Having thus described my invention, I claim as new and desire to secure by Letters Patent—

The design for an upholstery-trimming, composed of the body A, center band, B, and enlarged and puffed-up flowers C, substantially as shown and described.

In testimony that I claim the foregoing as my invention I have signed it this 12th day of May, 1880.

LEOPOLD LINDENTHAL.
